UNITED STATES PATENT OFFICE.

STEPHEN M. MARTIN, OF BRIDGEPORT, CONNECTICUT, ASSIGNOR TO HOLMES PRODUCTS, INC., OF NEW YORK, N. Y., A CORPORATION OF DELAWARE.

DESIGN FOR A REFRIGERATOR BOX.

Application filed October 27, 1928. Serial No. 28,669. Term of patent 14 years.

To all whom it may concern:

Be it known that I, STEPHEN M. MARTIN, a citizen of the United States, residing at Bridgeport, county of Fairfield, State of Connecticut, have invented a new, original, and ornamental Design for Refrigerator Boxes, of which the following is a specification, reference being had to the accompanying drawings, forming a part thereof.

Fig. 1 is a face view of a refrigerator box showing my new design.

Fig. 2 is a side view thereof.

I claim:

The ornamental design for a refrigerator box substantially as shown.

STEPHEN M. MARTIN.
